SPARK PLUG

Douglas W. Gregory, Jackson Heights, N. Y., assignor to The Firestone Tire & Rubber Company, Akron, Ohio, a corporation of Ohio

Application March 6, 1943, Serial No. 478,265

15 Claims. (CL 123—169)

This invention relates to spark plugs such as commonly are used with internal combustion engines, and more especially it relates to improvements in the manner of securing the center electrode of the plug in place.

In spark plugs of the character mentioned, it is common practice to make the center electrode of two parts, which parts are welded end to end. One part, which may be called the tip, is composed of a suitable alloy, usually of high nickel content, so as to withstand the high temperatures incidental to use without becoming corroded or oxidized. When mounted in the usual porcelain holder, said tip portion of the electrode which is at the lower end thereof, preferably is received in a bore or axial recess of somewhat larger diameter to provide clearance around the electrode, whereby thermal expansion of the latter in use will not impose strains upon the porcelain. The upper end portion of the center electrode may be composed of any inexpensive metal such as steel, and this portion of the electrode is sealed to the porcelain, and usually has threaded engagement therewith by means of threads formed on the electrode and complementary threads molded into the central bore of the porcelain.

Heretofore the sealing of the center electrodes in conventional spark plugs has been effected in either of two ways, namely, (a) by means of a liquid sodium-silicate base cement, (b) by means of a powder packed around an upset flange formed integral with the electrode, said flange being seated upon a ledge disposed within the axial bore of the porcelain. In using the first (a) method, it was customary to fill the center electrode hole with cement under pressure after the tip portion of the electrode had been inserted in the bore of the porcelain up to the threaded end of the upper end portion of the electrode, after which the electrode was worked to its ultimate position by screwing said threaded end portion thereof into the threaded portion of the porcelain. This method was not entirely satisfactory for the reason that cement was forced down the bore of the porcelain and around the tip portion thereof, and required to be washed therefrom to prevent operational difficulties, such as cracking of the porcelain due to lessened room for expansion of the electrode tip, or accelerated corrosion due to said cement. In general, such washing was a poorly regulated means for removing excess cement from the electrode tip. In using the second (b) method the powder was packed about the electrode and tamped into place, and

5 a separate screw having an axial bore to accommodate the upper end portion of an electrode wire was screwed into the threaded upper end portion of the porcelain to make a slip-fit contact with the outside or top of said porcelain.

10 This construction had the inherent disadvantage in that there was not positive contact between the center electrode and the so-called terminal screw, and the ignition connection was required to be made on said screw.

15 The chief object of this invention is to provide an improved spark plug construction wherein the aforementioned disadvantages of prior constructions are overcome. More specifically the invention aims to provide means whereby cement may be forced into exact permanent position under pressure without requiring the subsequent washing of cement from around the tip portion of the electrode; to provide a construction that obviates the formation of air pockets in the cement; 20 to lessen the strain on the internal threads of the porcelain insulator resulting from the tightening of the screw portion of the electrode structure; to provide a new and improved type of internal thread for porcelain insulators which is readily amenable to ceramic processing of the porcelain, and will result in an insulator of greater strength with a thread of increased holding and sealing possibilities; and to provide a porcelain insulator that is so constructed as to provide a natural path for the flow of excess cement to the exterior of the insulator, elsewhere than by way of the bore in which the electrode tip is received. Other objects will be manifest as the 25 description proceeds.

30 Of the accompanying drawings:

Fig. 1 is a diametric section through a spark plug embodying the invention;

Fig. 2 is a fragmentary section of the spark 40 plug shown in Fig. 1, on a larger scale, showing the operation of mounting and cementing the center electrode in the porcelain insulator;

Fig. 3 is a fragmentary section of a modified form of the invention;

45 Figs. 4 to 8 inclusive are diametric sections through other embodiments of the invention; and

50 Figs. 9 to 11 inclusive are fragmentary sections of other embodiments of the invention showing modified constructions at the top thereof.

Referring first to Fig. 1 of the drawings, there is shown a spark plug assembly comprising the usual metal shell 10, and a porcelain insulator 11, the latter being mounted in said shell and held in spaced relation thereto by soft metal gaskets

12, 12 in the usual manner. Positioned axially within the porcelain 11 is a center electrode that is designated as a whole by the numeral 13, said electrode being sealed in place by suitable or preferred cement 14. The plug also includes the usual ground electrode 15 that is mounted on the shell 10 at the lower end thereof. The porcelain 11 is formed with an axial aperture or bore in which the electrode 13 is received, and the specific shape of said aperture and the shape of the electrode received therein constitute the novel features of the improved plug.

The axial bore of the insulator 11 comprises a shallow, cylindrical recess or counterbore 18 at the top thereof, an internally threaded portion 19 immediately below the counterbore, a relatively short, smooth cylindrical portion 20 below the threaded portion, a frusto-conical downwardly tapered or bevel portion 21 at the lower end of portion 20, and a smooth cylindrical portion 22 extending from the small end of tapered portion 21 to the lower end of the insulator. The cylindrical portion 22 is smallest in diameter of any part of the axial aperture, and its length, as shown, is at least half the length of the insulator. The internal threads of the portion 19 are multiple in character, are rounded at crown and root, and are of relatively steep pitch or lead. Furthermore the threads are rugged in character so as to withstand substantial pressure without fracture.

The electrode 13 comprises a tip portion 24 constituting somewhat more than the lower half of the electrode, said tip portion being composed of the usual or preferred electrode alloy. In the assembled spark plug the tip portion of the electrode is received within the cylindrical portion 22 of the insulator aperture, the relative diameters of electrode and aperture being such that there is a small but definite space between them, as shown in Fig. 2, to enable thermal expansion of the tip portion 24 without strain upon the porcelain. The upper end of the said tip portion is welded to the lower end of a threaded structure 25, the weld being indicated at 26. The structure 25 may be formed of any inexpensive metal such as steel. The threaded portion 25 is formed exteriorly with threads that are shaped complementary to the internal threads in portion 19 of the insulator aperture, that is, they have the same rounded profile in transverse section and are of the same steep pitch or lead. The threads on electrode portion 25 are multiple, but of smaller number than the threads in the insulator. As shown, the threads in the insulator aperture are eight in number whereas there are but four threads on the electrode portion 25. The electrode portion 25 is received in portion 19 of the insulator in the assembled condition of the plug, and the electrode threads at 25 are symmetrically arranged so that they are engaged by alternate threads in the insulator. Obviously the number of threads in the insulator and on the electrode may differ from those shown and described, it being required only that the number of internal threads in the insulator be a multiple of the number of threads on the electrode.

At the upper end of threaded portion 25 the electrode is formed with an integral flange 28, and therebeyond is formed with a threaded terminal portion 29. The diameter of the flange 28 is greater than the diameter of the recess 18 in the top of the insulator 11 so that said flange will cover said recess in the finished plug. The terminal portion 29 is formed exteriorly with threads

of standard gauge and is adapted to receive the usual nut (not shown) by means of which an ignition wire may be secured to the electrode by being clamped between said nut and the flange

5 28. A sweeper collar or washer 30 of metal is mounted upon the electrode tip 24, said collar having a sliding fit thereon. While, as stated above, cylindrical portion 22 extends at least half the length of the insulator, it will be understood that this mode of cementing may be employed regardless of the length of the electrode used for feeding cement into the cement well. The extent of the proportions of relatively larger and smaller portions of the bore may therefore be varied and in some cases the reduced portion of the bore may be of only minor extent, as for example, the form of the invention illustrated in Fig. 6.

In the assembling of the spark plug from the several elements described, the sweeper collar 30 is positioned upon the electrode tip 24 at a distance from the weld 26 that is greater than the distance between weld and collar in the finished plug. Then cement is daubed on the electrode 20 to cover all the surface thereof between said sweeper collar and the flange 28. The cement may be of any usual or preferred composition, and since it is not a part of the present invention, no specific formula for the cement need be set forth here. The cemented electrode is then inserted 25 into the insulator aperture from the top thereof, the tip portion 24 of the electrode being received in portion 22 of said aperture. During this operation the sweeper collar 30 engages with and seats 30 itself upon the tapered portion 21 of the insulator aperture, with the result that further movement of the electrode causes tip portion 24 thereof to move through said collar. This causes the cement 35 that is immediately above said collar to be scraped from the electrode and to accumulate in the region 20 of the insulator aperture. By this time the threads on threaded portion 25 of the electrode engage with alternate internal threads of portion 19 of the insulator aperture, so that the electrode is worked into ultimate position by a 40 twisting movement, any entrapped air escaping upwardly along the unoccupied screw threads of the insulator aperture. The latter screw threads ultimately become filled with the cement, and the cement also fills any interstices between the electrode threads and insulator aperture threads with which they engage. Surplus cement is forced to 45 the top of the insulator whence it readily may be removed. The cement fills the counterbore 18 at the top of the insulator, and this cement adheres to the flange 28 of the electrode when the latter is 50 in its ultimate position, as shown in Fig. 1.

An alternative method of applying the cement to the plug is to insert the electrode therein so that the sweeper collar 30 is seated before the threaded portion 25 of the electrode enters the top of the insulator aperture, and then to inject the proper amount of cement into the aperture, there being sufficient space between the wall of the latter and the electrode to enable this to be done. The electrode is then worked into its ultimate position in the manner previously described.

From the foregoing it will be seen that the assembling of the improved plug readily is accomplished, and that cement is prevented from entering the lower aperture region 22 of the insulator. The feature of providing a relatively long pitch internal thread of coarse size in the insulator facilitates the manufacture thereof since it is practically impossible to manufacture porcelain

insulators having exact leads. For this reason insulators having internal threads having fine pitch and relatively small threads are often found to have bearing upon an inserted metal screw at one point only. The strength of such a joint then relies upon the cross-sectional area of said fine thread.

Conversely, a metal screw having a fine pitch can exert a tremendous force. It is therefore advantageous to have a heavy, rounded, long lead thread in the insulator. Furthermore, the raw clay of the insulator may be processed with the minimum of required accuracy, and the resulting product is free from acute angles at which stresses and strains are likely to concentrate. The multiple character of the threads shown utilizes the feature that a multiple point bearing or engagement may be had thereby notwithstanding shrinkage variation characteristics of the porcelain material.

The invention provides a superior spark plug, and achieves the other objects set out in the foregoing statement of objects.

The embodiment of the invention shown in Fig. 3 is similar to that previously described, and differs therefrom only in respect to the arrangement of the axial aperture in the porcelain, and the construction of the sweeper collar, the electrode otherwise being identical to the electrode shown in Figs. 1 and 2. Said sweeper collar, designated 33, is composed of relatively soft, deformable metal, such as copper or brass or a suitable alloy of sufficiently high melting point, and is cast upon the tip portion 24 of the electrode immediately below the weld 26 that joins said tip portion to the threaded portion 25 of the electrode, the arrangement being such that the sweeper collar is fixedly secured against movement relatively of the electrode. Initially the collar 33 is molded substantially to spherical shape, as indicated by the dotted lines, Fig. 3.

The porcelain insulator, designated 35, has the same external configuration as the insulator 11 previously described, but differs therefrom in the shape of its axial aperture. Thus the upper threaded portion 36 of the latter has but half the number of threads of the porcelain 11 previously described, that is, there are the same number of threads in the porcelain as there are on the threaded portion 25 of the electrode. Because of the steep pitch and multiple arrangement of the inter-engaged threads, there are relatively wide, continuous helical spaces between the same, which spaces are filled with cement in the finished plug. The axial aperture of the porcelain has a tapered portion 37 at the juncture of its threaded portion 36 and a reduced lower portion 38 wherein the tip portion 24 of the electrode is received, said tapered portion 37 being steeper or more acute than tapered portion 21 of the embodiment previously described.

The porcelain 35 and electrode are assembled substantially in the same manner as in the embodiment previously described, with the cement 14 binding the structures to each other. During the assembling of the plug, the sweeper collar 33 in spherical form seats in the tapered portion 37 of the porcelain aperture before the electrode is moved to its ultimate position, and provides a stop to prevent the flow of cement therebeyond and into portion 38 of the porcelain aperture. Continued axial movement of the electrode into the porcelain deforms the collar 33 to the shape shown in full lines in the drawings.

In the embodiment of the invention shown in

Fig. 4, the electrode has a smooth tip portion 40 at its lower end, which tip portion is welded at 41 to a portion 42 of larger diameter than has its upper end portion provided with a flange 43, and a terminal threaded portion 44 for the reception of the usual terminal nut (not shown). Immediately below the flange 43 the electrode portion 42 is formed with a single screw thread 45 of standard pitch, which thread extends at least a third of the length of the said portion 42. There is a sweeper collar 30 slidably mounted upon the electrode tip 40. The porcelain, which is designated 48, is formed with an axial recess within which said electrode is received, said recess including a lower portion 47 that closely encircles but does not touch the electrode tip 40; a cylindrical portion 48 thereabove that embraces the unthreaded portion 42 of the electrode but is substantially spaced thereabout, there being a tapered portion 49 at the juncture of portions 47 and 48, and an upper threaded portion 50 adapted to receive the threaded portion 45 of the electrode. At the top of the porcelain the aperture therein includes a counterbore 51. The threads of portion 50 differ from standard threads in that their crowns are cut off or truncated, with the result that when electrode portion 45 is threaded into aperture portion 50 there is a recess between the roots of the threads of the electrode and the tops of the threads of the porcelain aperture. This recess is continuous and extends from the aperture region 48 to the counterbore 51 whereby surplus cement 14 may escape upwardly to the top of the porcelain and be removed therefrom during the assembling of the plug. The cement may be applied in any suitable manner as hereinbefore explained. A metal washer 52 is mounted upon the electrode before assembling the plug, said washer being positioned between the electrode flange 43 and the top of the porcelain insulator in the finished plug. The electrode carries the sweeper collar 30 that seats on tapered portion 49 of the porcelain aperture in the assembled condition of the plug.

In the embodiment of the invention shown in Fig. 5 a porcelain insulator 54 is formed with an axial bore comprising a counterbore 55 at the top thereof, a smooth cylindrical portion 56 immediately therebelow, a threaded portion 57 immediately below portion 56, the bottom of said threaded portion merging with the large end of a short tapered portion 58 that opens into a smooth cylindrical portion 59 constituting the lower end portion of the aperture. The threaded portion 57 of said aperture is formed with relatively large dual threads of relatively steep pitch. Received in the porcelain aperture is an electrode comprising a tip portion 60 that is received in portion 59 of the aperture, and a generally smooth portion 61 thereabove that is formed at its lower end with a pair of outstanding lugs 62, 62, said lugs being disposed at diametrically opposite positions on the electrode and engaging respective threads of the threaded portion 57 of the porcelain. Above portion 61 the electrode includes a threaded portion 63 formed with a single thread of standard size, and above said portion 63 is a flange 64 and the usual threaded terminal portion 65 for receiving a nut (not shown). The electrode carries a sweeper collar 66 that seats on tapered region 58 of the porcelain in the assembled condition of the plug, and a washer 67 beneath the flange 64 that seats upon the top of the porcelain.

In the assembling of the plug, the lugs 62 en-

gage with the threaded portion 57 of the porcelain aperture whereby the electrode is moved axially into position as it is manually rotated. Cement 14 is applied in either manner hereinbefore described. The arrangement provides ample clearance between electrode and porcelain for surplus cement to move to the top of the porcelain aperture, the collar 68 preventing the cement from moving downwardly into portion 58 of said aperture. The threads 63 on the electrode serve to effect an intimate bond between the cement and electrode, and the threads in portion 57 of the porcelain aperture assure an intimate bond between cement and porcelain.

In the embodiment of the invention shown in Fig. 6 a porcelain insulator 69 is formed with an axial bore having a counterbore 70 at the top thereof, a relatively long, smooth, cylindrical portion 72 below said counterbore, a relatively short threaded portion 73 below portion 72, and a relatively short, smooth cylindrical portion 74 at the lower end thereof. The thread of portion 73 is large and rounded, and also is a single thread. Receivable in the porcelain aperture is an electrode having a tip portion 75 receivable in portion 74 of said aperture. Said tip portion is welded at 76 to an upper, and major portion 77 that is receivable in portion 72 of the porcelain aperture, said electrode portion 77 being of substantially smaller diameter than said aperture to provide space therebetween for cement 14. Adjacent its lower end the portion 77 of the electrode is formed with a short screw thread 78 that is complementary to screw thread 73 of the porcelain aperture, said thread 78 extending once around electrode portion 77. Near its upper end the electrode portion 77 is formed with screw threads 79 of standard pitch, this threaded portion of the electrode being receivable in aperture portion 72 of the porcelain with ample clearance, and in the counterbore 70, said threaded portion being surmounted by a flange 80 and the usual terminal thread 81. A metal washer 82 is disposed between the flange 80 and the top of the porcelain. This plug is essentially similar to that shown in Fig. 5 except that the meshing of threads 73, 78 serves to prevent the flow of cement 14 into the portion 74 of the porcelain aperture, whereby the use of a sweeper collar is dispensed with.

In the embodiment of the invention shown in Fig. 7, a porcelain insulator 84 is formed with an axial aperture comprising a portion 85 of relatively short length and small diameter at the lower end thereof, a longer portion 86 of cylindrical shape and larger diameter disposed thereabove and joining portion 85 by way of a short tapered portion 87, a threaded portion 88 above portion 86 and formed with dual threads of large size, rounded profile, and steep pitch, and a counterbore 89 at the upper end of said aperture. Received in said aperture is an electrode comprising a tip portion 90 disposed in aperture portion 85 and having a sweeper collar 91 slidably mounted thereon and seatable upon tapered portion 87 of the aperture, said tip portion being welded at 92 to a major portion 93 of larger diameter disposed within aperture portions 86 and 88. Electrode portion 93 is formed with a pair of outstanding lugs 94, 94 at diametrically opposite points thereon, which lugs engage with the respective threads of threaded portion 88 of the porcelain. At its upper end electrode portion 93 is formed with an integral flange 95 and a terminal threaded portion 96, the bottom face of said flange being formed with a concentric beveled

boss 97 that will project into the counterbore 89 of the porcelain in the finished plug. Also mounted in said counterbore 89 is a washer 98 of deformable metal, which washer is shaped substantially complementary to the boss 97 so as to be engaged thereby and thus to provide an effective closure for the upper end of the porcelain aperture. The plug includes the usual cement 14 between electrode and porcelain, the cement being applied in any manner heretofore described.

In the embodiment of the invention shown in Fig. 8, there is a porcelain insulator 100 that is formed with an axial aperture comprising a counterbore 101 at the top thereof, a smooth cylindrical portion 102 of relatively short length extending downwardly therefrom, and a relatively long smooth cylindrical portion 103 of larger diameter than portion 102 extending to the lower end of the insulator, there being a shoulder 104 at the juncture of portions 102 and 103. Mounted in said aperture is an electrode comprising a relatively short tip portion 105 at the bottom thereof and a relatively long major portion 106 of larger diameter constituting the remainder of the electrode, said major portion being formed with terminal threads 107 at its upper end. The electrode is formed with an integral flange 108 on portion 106, and has a metal collar 109 slidably mounted on tip portion 105. The diameter of flange 108 and collar 109 is but slightly smaller than the diameter of aperture portion 103 so that said flange and collar may move axially of the latter, yet will obstruct the passage of cement, shown at 14. In the finished plug the electrode 106 is disposed within the porcelain aperture, flange 108 abutting or substantially abutting shoulder 104 of the porcelain and collar 109 abutting electrode portion 106 at the juncture of the latter and tip portion 105. A washer 110 is seated in counterbore 101 and a flat nut 111 is threaded onto portion 107 of the electrode to retain the latter in place. The space between electrode portion 106 and the wall of aperture portion 103 is filled with cement 14. In the assembling of this embodiment of the invention, electrode portion 106, below the flange 108, initially is covered with cement, and then the electrode is mounted in the porcelain aperture from the bottom thereof. Thereafter the collar 109 is forced upwardly on tip portion 105 of the electrode to clean the same of cement and to pack the latter into the space thereabove.

In the structure shown in Fig. 9, a porcelain insulator 114 is formed at the top thereof with a counterbore 115 in which is received a soft metal washer 116, there being a smooth cylindrical aperture portion 117 extending downwardly from said counterbore. The washer 116 is of substantially smaller diameter than the counterbore, and of greater thickness than the depth of the counterbore. Received in the porcelain aperture is an electrode structure 118, the upper end of which is formed with the usual terminal threaded portion 119, there being a flange 120 on the electrode immediately below said threaded portion, which flange bears on the washer 116 in the finished form of the plug. The under side of the flange 120 is formed with a concentric, beveled boss 121, and the central opening in washer 116 is shaped complementary to said boss to provide effective engagement therebetween. The arrangement is such that the washer may be deformed by the tightening of the electrode in the porcelain whereby a superior seal at the upper end of the porcelain aperture is effected.

In the structure shown in Fig. 10, a porcelain insulator 124 is formed with an axial aperture 125 in which is received a cylindrical electrode member 126 of smaller diameter to provide space for a quantity of cement 14 therebetween. The upper end of the electrode is formed with the usual terminal threaded portion 127 and integral flange 128 below said threaded portion. Between the flange 128 and the top of the porcelain is a metal washer 129 having an axial aperture as large in diameter as the porcelain aperture 125, and mounted upon the electrode 126 is a metal bushing 130 that extends through said washer and into the top of said aperture. The lower end of bushing 130 is tapered or beveled, the arrangement being such that the bushing will enter the porcelain aperture and compact the cement therein as the electrode is moved downwardly to position during the assembling of the plug.

In the structure shown in Fig. 11, a porcelain insulator 132 is formed with an axial aperture that is formed with standard screw threads 133 at its upper end, has an annular tapered region, 134, immediately therebeneath, which tapered region opens into a smooth cylindrical region 135 at its lower and smaller end. Received in the porcelain aperture is an electrode herein shown as an assembled structure comprising an upper element consisting of a terminal threaded portion 136, an integral flange 137 therebeneath adapted to bear against the upper end of the porcelain, and a threaded portion 138 received in the threaded aperture portion 133 of the porcelain. The threaded portion 138 of the electrode is axially recessed from its lower end to receive a lower electrode element 139 therein with a force fit, the upper end of the element 139 being knurled as shown to assure a secure union with the superposed structure. Electrode portion 139 is disposed in aperture portion 135 of the porcelain, and is smaller in diameter than said aperture portion to provide a space in which cement 14 is placed. Mounted upon the electrode element 139 immediately below the threaded portion 138 of the upper electrode element 138 is a sweeper collar 140 that seats in the tapered portion 134 of the porcelain aperture to provide an effective seal against the cement 14 in the space therebelow. The collar is shown as being shaped complementary to its tapered seat 134, but originally the collar is cast upon the element 139 in spherical form, and is deformed to conical shape as the electrode is threaded axially into the porcelain. In this respect the collar is similar to collar 33, Fig. 3.

In the embodiments of the invention illustrated in Figs. 4, 5 and 7 the junction of the large and small portions of the center electrode form a shoulder confronting the sweeper collar. For example, in Fig. 4, a shoulder is formed at 41, confronting sweeper collar 30. When the center electrode 42 expands due to motor heat, the shoulder at 41 is forced toward sweeper collar 30 compressing the cement against the sweeper collar and tightening the seal at this point. The degree of this compressive force can be controlled by varying the distance between the nearest point of positive engagement with the insulator and the shoulder at 41, this variation being illustrated in Figs. 5 and 7. In Fig. 5 the point of positive engagement of the center electrode with the porcelain is at lugs 62 only a short distance above the shoulder formed by the junction of the smaller and larger electrodes, and expansion of the center electrode will result in only a

small degree of compression of the cement. In Fig. 7 the point of positive engagement of the center electrode with the porcelain is at lugs 84, a considerable distance from the shoulder at 82, resulting in a greater degree of compression of the cement.

The foregoing illustrative embodiments of the invention clearly show various constructions by which the cement employed about the electrode of a spark plug is readily positioned and retained in the desired local regions within the porcelain, whereby the objects of the invention are achieved.

Modification may be resorted to without departing from the spirit of the invention, or the scope thereof as defined by the appended claims.

I claim:

1. A spark plug comprising a porcelain insulator having an axial aperture therethrough that is of smaller diameter at its lower end portion and larger diameter thereabove with a tapered region between the regions of different diameters, a one-piece metal electrode received in said aperture and spaced from the wall thereof to provide space for the reception of cementitious material in plastic form, the lower end portion of the electrode being of reduced diameter, a member mounted on the reduced end portion of the electrode and movable relatively thereof adapted to seat on the tapered region of the porcelain aperture during the mounting of the electrode in said aperture, before said electrode moves to its ultimate position in the latter, thus preventing flow of cementitious material into the lower end portion of said aperture, and threaded means for effecting longitudinal movement of the electrode into the porcelain aperture during the assembling of the plug.

2. A spark plug comprising a porcelain insulator having an axial aperture therethrough that is of reduced diameter at its lower end portion and has a tapered region connecting said region of reduced diameter with the region of larger diameter thereabove, a one-piece metal electrode received in said aperture and spaced from the wall thereof to allow space for the reception of cementitious material in plastic form, a member mounted on the lower end portion of the electrode and movable relatively thereof adapted to seat upon the tapered region of the porcelain aperture during the mounting of the electrode in said aperture, before said electrode is moved to its ultimate position therein, thus obstructing flow of cementitious material into the lower end portion of said aperture as the electrode moves thereto, and cooperating screw thread means on the electrode and in the porcelain aperture to effect longitudinal movement of the electrode in its entirety during assembling of the plug, said thread means being so constructed and arranged as to enable cementitious material to move therewith.

3. A spark plug as defined in claim 2 wherein the thread means are of steep pitch and rounded at crown and roof.

4. A spark plug as defined in claim 2 wherein the thread means consists of multiple threads of steep pitch.

5. A spark plug as defined in claim 2 wherein the thread means consists of a plurality of threads of steep pitch on the electrode, and the number of threads in the porcelain aperture is a multiple of the number of threads on the electrode.

6. A spark plug as defined in claim 2 wherein the thread means consists of multiple threads of steep pitch, the threads being relatively widely

spaced apart axially of the electrode and insulator aperture to provide space therebetween for the flow of cementitious material.

7. A spark plug as defined in claim 2 wherein the thread means comprises a single thread of steep pitch formed in the porcelain, and a thread of complementary size and pitch extending once around the electrode.

8. A spark plug comprising a porcelain insulator having an axial aperture therethrough, a one-piece metal electrode received in said aperture, the latter being of smallest diameter at its lower end portion, and being larger thereabove to provide substantial space about the electrode, there being a tapered region in said aperture between the regions thereof of different diameter, a member on the lower end portion of the electrode and movable relatively thereof adapted to seat on the tapered region of the porcelain aperture during mounting of the electrode, before the latter is moved to its ultimate position in the porcelain aperture, thus sealing off the lower end portion of the porcelain aperture against the flow of cementitious material as the electrode moves thereinto, and a quantity of cement in said porcelain aperture above said member and about said electrode therein.

9. A combination as defined in claim 8 wherein the sealing member is a sweeper collar slidably mounted on the lower end portion of the electrode.

10. A combination as defined in claim 8 wherein the sealing member is a mass of soft metal fixed on the electrode and deformed into conformity with the tapered region of the porcelain aperture during the assembly of the plug.

11. A spark plug comprising a porcelain insulator having an axial aperture therethrough, which aperture has regions of different diameters connected by an intermediate tapered region, an electrode received in said aperture, a charge of cement about said electrode in one region of said aperture, and a deformable metal collar secured on said electrode and shaped to conformity with said tapered region of the porcelain aperture to isolate the cement in one region of the latter.

12. A spark plug comprising a porcelain insulator formed with an axial aperture therethrough, which aperture is of smaller diameter at its upper end portion to provide an internal shoulder, an electrode received in said aperture and formed with a flange abutting said shoulder, said electrode having a reduced lower end portion, a quantity of cement around said electrode within said aperture, and a collar slidably mounted upon the reduced portion of the electrode and receivable within the porcelain aperture to confine the cement therein between said flange and said collar.

13. A spark plug comprising a porcelain insulator having an axial aperture therethrough, a

metal electrode received in said aperture, said aperture having a smaller diameter at its lower end adjacent the sparking end of the plug and a larger diameter thereabove to provide a substantial space about the electrode, there being a shouldered region in said porcelain insulator between said portions of different diameter, said electrode having a lower portion of smaller diameter and an upper portion of larger diameter, the junction between said different diameters constituting a shoulder confronting the shoulder in said insulator, a quantity of cement in said aperture confined between said shoulders about said electrode for sealing the latter in said insulator, and means on said electrode positively engaging a portion of said insulator in a region thereof spaced above said shoulders, whereby axial elongation of said metal electrode resulting from heat of operation will cause the shoulder on said electrode to be forced toward the shoulder on said insulator, compressing said cement therebetween and tightening the seal between said electrode and said porcelain.

14. A spark plug comprising a porcelain insulator having an axial aperture therethrough, a metal electrode received in said aperture, portions of the latter being substantially larger in diameter than the electrode for the reception of plastic cementitious material, a member mounted on the electrode and movable relatively thereof for preventing flow of cementitious material to the lower end of the porcelain aperture, and cooperating screw thread means on the electrode and in the porcelain aperture to effect longitudinal movement of the electrode relatively of the porcelain during assembly of the plug, the electrode threads being formed adjacent the upper end thereof of conventional size, shape, and pitch, the porcelain aperture being formed with threads of complementary size and pitch, the last mentioned threads having their crowns truncated to provide a continuous passage for cementitious material at the roots of the electrode threads in the assembled plug.

15. A spark plug comprising a porcelain insulator having an axial aperture therethrough, which aperture is formed with a counterbore at the top thereof, a metal electrode received in said aperture, a charge of cementitious material within the porcelain aperture about the electrode therein, means within said aperture preventing flow of the cementitious material to the lower end thereof, and means on the electrode effecting sealing of the upper end of the porcelain aperture at said counterbore, said means comprising a metal washer on the electrode received in the counterbore in the porcelain, and a flange on the electrode formed on its under side with a concentric beveled boss engageable with the inner circumference of said washer.
